UNITED STATES PATENT OFFICE.

EDMUND MEREDITH, OF PHILADELPHIA, PENNSYLVANIA, ASSIGNOR TO THE PENNSYLVANIA GLOBE GAS LIGHT COMPANY, OF PENNSYLVANIA.

LOCOMOTIVE HEAD-LIGHT.

SPECIFICATION forming part of Letters Patent No. 416,116, dated November 26, 1889.

Application filed May 8, 1889. Serial No. 309,968. (No model.)

To all whom it may concern:

Be it known that I, EDMUND MEREDITH, a citizen of the United States, residing at Philadelphia, in the county of Philadelphia and State of Pennsylvania, have invented certain new and useful Improvements in Locomotive Head-Lights; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to that form of lamps known as "locomotive head-lights," and has for its object the provision of a well-constructed, readily-operated, and efficient device for the purpose indicated.

The invention consists in the construction and arrangement of parts by which these objects are attained, as hereinafter set forth, and pointed out in the claims.

The accompanying drawings illustrate the invention.

Figure 1 is a plan view of the device. Fig. 2 is a rear elevation showing certain portions removed. Fig. 3 is a rear elevation of a portion of the reservoir, showing the segmental guide. Fig. 4 is a transverse central section of the device. Fig. 6 is an enlarged sectional view of the wick-holder. Fig. 5 is a sectional view of a portion of the reservoir, showing the vent upon it.

Similar letters of reference indicate corresponding parts in all the figures where they occur.

A is the oil-reservoir, which may be of any convenient form, and a a are screw-studs upon it to receive the reflector. On one side of the oil-reservoir, and projecting beneath it, is a vertical chamber A' , to which the oil has access by a suitable passage, and to one side of the chamber the oil-feeding and wick-holding cylinder A^2 is attached. This cylinder is made in the usual Argand style and provided at the bottom with a foraminous air-screen a^2 . The wick-holder A^3 is a cylinder with a bottom extension a^3 , and the wick

an asbestos top, over which the holder is bent, as shown at a^4 , at the top, and provided with slots a^5 in the bend to feed oil to the flame, while the exterior solid portion of the bend prevents the flame from reaching too far down the wick when turned up. In this way an almost imperishable wick is provided.

Over the top of the oil-cylinder is placed a burner-cap B, which consists of a foraminous cylinder b , which surrounds an imperforate shorter cylinder or sheath b' , which fits over the oil-cylinder and holds the foraminous cylinder out from the oil-cylinder, with a space between them for air to flow through to the exterior of the wick-top, and prevents drafts and gusts. Upon the top of the foraminous cylinder a cap-piece b^2 is hinged, which has a central opening coextensive with the diameter of the wick.

Upon the top of the oil-reservoir, at a height above the level of the oil, either in the reservoir or in the side chamber, a wick-raising shaft C is held in suitable boxing C' . One end of the shaft projects into the chamber A' , and the other reaches back of the reservoir. To the end in chamber A' is secured a crank C^2 , to which a pitman or link C^3 is attached, which extends down to the lower portion of the chamber A' , where it is joined to a swinging arm C^4 , pivoted to a fixed part of the lamp, and a pin C^5 at the point of junction of arm C^4 and link C^3 affords a means for engaging a hook a^6 on extension a^3 of wick-holder A^3 . The hook is open upon the side, and by suitably turning the holder it can be made to engage the pin C^5 ; or when it is desired to disengage it and remove the holder and wick it can be turned in the opposite direction sufficiently to take the hook away from the pin. When the hook in the holder is engaged with the pin, an upward movement of the pin will raise the wick and a downward movement will lower the wick. The movement of the pin is effected through the medium of the pitman C^3 , crank C^2 , and shaft C. The shaft C bears at the end opposite to the crank C^2 an operating-crank D, which is manipulated to operate the wick-holder. A segmental guide E is provided on the back of the oil-reservoir, and the end of crank D rides

beneath it and bears a screw which projects in front of the guide and carries a pinching-nut *d*, which can be screwed down to set the crank at any point to regulate the elevation 5 of the wick. By this means the wick can be raised or lowered and held reliably at any point of elevation.

The oil-reservoir is provided with a vent, which consists of an elongated chamber *F*, 10 set upon the top of the oil-reservoir, having a depressed center *f*, which nearly meets the top of reservoir, with an opening *f'* into the reservoir on one side of the depressed center, and an opening *f''* out into the air on the 15 other side. By this means the reservoir is thoroughly ventilated and kept free of gases, while no oil can escape through the vent by splashing and shaking. The reservoir is also provided with the usual filling-aperture and 20 cap *A**. A stop may be placed upon the guide to hold the crank from going too far to the right and dropping the wick too low.

Having thus described my invention, what I 25 claim, and desire to secure by Letters Patent, is—

1. In a lamp, the combination of the oil-reservoir and vertical oil-chamber on the side thereof, and an oil-feeding cylinder secured to the vertical chamber and communicating 30 therewith, with a wick-holder adjustable in the said cylinder and a crank and pitman operated in the chamber to regulate the elevation of the wick, as set forth.

2. In a lamp, the combination, with an adjustable wick-holder, of a pivoted arm and pitman swiveled together and bearing a pin connected with the wick-holder, a crank connected to the pitman at the top, and a shaft, to which the crank is fixed, having an operating-crank with a pinching-screw upon it, and 35 a segmental guide on which the pinching-screw operates to hold the shaft in any desired position, as set forth.

3. In a lamp, the combination, with the oil-reservoir, vertical oil-chamber, and oil-cylinder connected thereto, of a wick-holder in 40 said cylinder, operating devices therefor in the oil-chamber, a shaft connected to said operating devices, and a box upon the top of the oil-reservoir, in which the shaft is held above 45 the level of the oil, as set forth.

4. An oil-reservoir provided with a vent consisting of an elongated chamber secured upon the top thereof, having a depressed center and an opening into the reservoir on one 50 side of the depressed center and one into the air on the other side of said center, as set forth.

In testimony whereof I affix my signature in presence of two witnesses.

EDMUND MEREDITH.
